UNITED STATES PATENT OFFICE.

CHARLES EDMUND CLEWS AND ARTHUR WYNDHAM BEERE, OF AUCKLAND, NEW
ZEALAND, ASSIGNEES TO PERCY NICHOL KINGSWELL, OF AUCKLAND, NEW
ZEALAND.

LIFTING JACK AND HAULER.

Application filed June 6, 1922. Serial No. 566,291.

To all whom it may concern:

Be it known that we, CHARLES EDMUND CLEWS and ARTHUR WYNDHAM BEERE, both citizens of the Dominion of New Zealand and subjects of the King of Great Britain, and residing at Prospect Terrace, Paeroa, Auckland, and Prospect Place, Auckland, respectively, both in the Provincial District of Auckland, have invented certain new and useful Improvements in Lifting Jacks and Haulers, of which the following is a specification.

This invention relates to jacks for lifting and hauling objects and particularly to the construction of jack described and claimed in the specification attached to application for Letters Patent Number 1,376,136 dated 26th April 1921 in the name of Charles Edmund Clews.

20 The object of the invention is to provide improvements, whereby the jack constructed and operated as described in the aforesaid specification will be rendered more positive in its action than heretofore, besides 25 which the operation of the jack will be facilitated and the latter given longer life.

The main feature of the invention is the provision of means for ensuring the engagement and retention in the rack or spear 30 or the chain, in a positive and certain manner whenever required of the pawl employed for holding the load, while the grip of said rack or spear or the chain, by the pawl on the operating lever is being 35 changed.

This is enabled to be done by constructing and mounting the operating lever of the jack, so that its inner end, when moved downwards, will bear against and force the 40 load holding pawl into engagement with the rack or spear or the chain, such engagement being ensured and continued during the time that the pawl on the operating lever is disengaged from the rack or spear 45 or the chain.

A further feature of the invention is the provision on the inside of the casing at the side against which the rack or spear or the chain is forced by the action of the 50 pawls, of a vertical rib or strip at each side of which the links of the chain, when the latter is employed, pass, the rollers of the chain bearing against the rib or strip so as to facilitate movement of the chain 55 through the casing and giving longer life

to the latter and the chain than where the links are forced hard into contact with the casing side. Owing to the insertion of the rib or strip in the casing, it becomes necessary to groove or recess the rack or spear, 60 in order that same can be used in place of the chain.

Referring to the accompanying drawing in conjunction with which the invention will be more particularly described:—

65 Figure 1 is a sectional elevation of the jack set for lifting a load.

Figure 2 is a similar view showing the jack set for lowering a load.

Figure 3 is an elevation (broken) showing a chain used instead of a rack.

Figure 4 is a part plan view with a rack or spear in the jack, while

Figure 5 is a similar view of Figure 4, but showing a chain in the jack.

In the drawing 1 is the casing, 2 the rack or spear, 3 the chain and 4 the guide between which and the casing side the rack or spear 2, or the chain 3 works. 5 is the operating lever fulcrumed at 6 to the casing, and 7 is the pawl carried by said lever. 8 is the pawl used for holding the load during the time the grip of the rack or spear 2 or the chain 3 by the pawl 7 is being changed. 9 is the rocking arm carrying 85 springs 10, 11, 12, and mounted and adapted to be operated for the purpose set forth as described in the before mentioned specification.

The inner or forked end 5^a of the operating lever 5 in which the pawl 7 is pivoted is bevelled and has its lower corners rounded as shown so that on downward movement of said forked end 5^a occurring the latter makes contact with and fits against an inclined surface 17 on the back of the upper end of the pawl 8.

The opening 18 at the top of the casing through which the rack or spear 2, or the chain 3 passes has at one side an under cut or inclined surface 19, between which and the upper portion of the pawl 7 an upwardly curved spring 20, secured to the inside of the upper end of the casing 1 projects.

On the inner side of the side 1^a of the casing 1, a vertical rib or strip 21 is provided, while at the top of said side 1^a a roll or outwardly and downwardly bent portion 22 is formed, over which the chain 3 (when used) hangs as shown.

This rib or strip 21 is specially provided to suit the chain 3 when the latter is employed, said rib or strip being of such a width that the links 23 of the chain pass at each side of same and so enable the rollers 3^a of the chain to make contact with and run against said rib or strip 21 whereby the passage of the chain through the casing is facilitated by minimizing the friction resulting from pressure of the chain 3 against the side 1^a, by the action of the pawls 7, 8.

The rack or spear is grooved as at 24, to enable it to accommodate the rib or strip 21, thereby enabling either the rack or spear, or the chain to be employed as desired.

To use the jack for lifting or hauling purposes the handle 16 is operated to cause the springs 10 and 11 to press against the tail ends of the pawls 8 and 7 as shown in Figure 1 so that the upper ends 8^a and 7^a of said pawls normally engage in the teeth 2^a, or in the chain, according to which is employed.

The outer end of the operating lever 5 is then worked upwards and downwards and on downward movement of the pawl 7 taking place, the upper end 7^a of the latter slips down over the teeth 2^a or over the roller 3^a of the chain 3 the upper end 8^a of the pawl 8 being in the meantime forced by the spring 10 and inner end 5^a of the lever 5 into the teeth 2^a or into the chain 3 to hold the rack, spear, or the chain, against downward movement until such time as the upper end 7^a of the pawl 7 is again inserted in the teeth 2^a or grips the chain 3, on the outer end of the operating lever 5 being depressed to force the rack or spear 2 or the chain 3 through the casing 1.

In order to enable a load to be lowered gradually, the reversing handle 16, is operated to bring the rocking arm 9 to the position shown in Figure 2, with the springs 11, 12 pressing against the tails of the pawls 8 and 7 respectively, so that normally the upper end 8^a and 7^a of said pawls will be kept from engaging, or will be clear of the rack or spear 2, or the chain 3.

The operating lever 5 is then worked upwards and downwards as before, upward movement of the pawl 7 causing its upper portion to make contact with the spring 20, whereby the end 7^a of said pawl is forced to engage in the teeth 2^a of the rack or spear 2, or to grip a roller 3^a of the chain 3 as the case may be and to raise said rack or spear, or the chain sufficiently to enable the upper end 8^a of the pawl 8 to spring out of or to free itself from said rack or spear 2 or the chain 3, under the influence of the spring 11.

The weight of the load is now taken by the pawl 7, which is then lowered to permit the rack or spear 2, or the chain 3 to descend in the casing 1.

As the inner or forked end 5^a of the oper-

ating lever 5 descends, it makes contact with the surface 17 on the back of the pawl 8, and forces the upper end 8^a of the latter into the teeth 2^a of the rack or spear 2 or so as to grip a roller 3^a of the chain 3. 70 The pawl 8 now takes the weight of the load and the continued downward movement of the end 5^a of the lever 5, results in the pawl 7 being lowered, until its upper end 7^a is enabled to spring out of and clear the teeth 2^a, or the chain 3 as the case may be, the end 5^a meanwhile bearing against and retaining the upper end 8^a of the pawl 8 in engagement with the teeth 2^a of the rack or spear or in the chain 3. 75

Following this the inner end 5^a of the lever 5 is raised again to enable the pawl 7 to obtain a fresh grip of the rack or spear, or of the chain, the fresh grip by the pawl 7 being obtained before the end 5^a of the lever 5 clears the back of the pawl 8 sufficiently, to enable the latter to spring or come out of engagement with the rack or spear, or the chain, should by any chance the weight of the load be even momentarily taken off said pawl 8. 80

While the weight of the load is being borne by the pawl 8, the load is safely held, as owing to the end 5^a of the lever 5 being against the lever 8, the latter must remain in the teeth 2^a or in the chain 3 against the action of the spring 11, even should the rack or spear or the chain be relieved of downward pressure. 90

If the lever 5 be accidentally moved to the position where its end 5^a clears the lever 8, the load cannot drop any appreciable extent, because in this position the pawl 7 is engaged in the teeth 2^a or in the chain 3, and the slightest downward movement of said lever 7, has the effect of immediately forcing the pawl 8 into engagement with the teeth 2^a or chain 3 as before described. 100

What we do claim and desire to obtain by Letters Patent of the United States is:—

1. Apparatus of the kind described comprising a load bearing member operable through a casing; a pawl pivoted to the latter adapted to hold said member against the weight of the load borne thereby; an operating lever pivoted to said casing carrying at one end a pawl adapted to engage and operate said member; said lever having its pawl carrying end formed to force the load holding pawl into engagement with the load bearing member on said inner end being lowered. 110

2. Apparatus of the kind described, comprising a casing with an internal rib or strip on one side; a load bearing member with side portions which pass at each side of said rib or strip operable through said casing; a pawl with an inclined upper surface pivoted to the latter, adapted to hold 120

said member against the weight of the load borne thereby; an operating lever pivoted to said casing and having a bevelled and forked inner end in which a load shifting pawl is pivoted; said inner end being positioned so that on being lowered it engages the back of the load holding pawl and forces same into engagement with the load carrying member.

10 3. In apparatus of the kind described, wherein a load shifting pawl and a load holding pawl are employed; an operating lever carrying the load shifting pawl, and having its inner end formed to force the load holding pawl into engagement with the load bearing member, on said inner end being lowered.

15 4. In apparatus of the kind described wherein a load shifting pawl and a load holding pawl are employed, an operating lever with a forked inner end in which the load shifting lever is pivoted, the ends of said fork being bevelled and provided with rounded lower corners; an inclined surface 20 on the back of the upper portion of the

load holding pawl, against which the forked end of the operating lever makes contact, and forces said pawl into engagement with the load bearing member on the forked end of the lever being lowered.

25 5. In apparatus of the kind described an internal rib or strip at one side of the casing, and a load bearing member working against said casing side, and provided with side portions which pass at each side of the 30 rib or strip.

6. In apparatus of the kind described an internal rib or strip at one side of the casing and a roller chain working through the 35 casing against said side, so that the rollers run against said rib or strip and the links pass at each side thereof.

40 In testimony whereof we have signed our names to this specification in the presence of two witnesses.
